CLAIM

The ornamental design for the pickaxe handle, as shown and described.

DESCRIPTION

FIG. 1 is a perspective view of the pickaxe handle, in accordance with the present invention;

FIG. 2 is front view of the embodiment of the pickaxe handle depicted in FIG. 1;

FIG. 3 is a side view of the embodiment of the pickaxe handle depicted in FIG. 1;

FIG. 4 is a top view of the embodiment of the pickaxe handle depicted in FIG. 1;

FIG. 5 is a bottom view of the embodiment of the pickaxe handle depicted in FIG. 1;

FIG. 6 is a perspective view of a second embodiment of the pickaxe handle, in accordance with the present invention;

FIG. 7 is a front view of the embodiment of the pickaxe handle depicted in FIG. 6;

FIG. 8 is a side view of the embodiment of the pickaxe handle depicted in FIG. 6;

FIG. 9 is a top view of the embodiment of the pickaxe handle depicted in FIG. 6; and,

FIG. 10 is a bottom view of the embodiment of the pickaxe handle depicted in FIG. 6.

The claim is directed to the upper and lower portions of the handle as shown.
